Specification of Letters Patent.

Patented July 11, 1922.

Application filed February 6, 1917. Serial No. 146,939.

(GRANTED UNDER THE PROVISIONS OF THE ACT OF MARCH 3, 1921, 41 STAT. L., 1313.)

To all whom it may concern:

Be it known that I, PAUL MANSEL, a subject of the German Emperor, and resident of Siemensstadt, near Berlin, Germany, have 5 invented certain new and useful Improvements in Clocks (for which I have filed application in Germany Jan. 20, 1916, Patent No. 325,934), of which the following is a specification.

10 My invention refers to clocks and more especially to clocks provided with a striking work actuated by electricity. The object of the invention is an electric striking work adapted to automatically strike the hours 15 and half hours after having been set going by suitable mechanism. The improved striking work is designed principally to be applied to electric branch clocks.

In the striking work according to the 20 present invention the actuating power is furnished by an electromagnet in combination with a rack striking work of well known construction. The electromagnet is intermittently excited, corresponding to the desired 25 number of strokes, the current supply being controlled by a contact device controlled by the strike work itself.

In the drawings affixed to the specification and forming part thereof the preferred form 30 of a strike work according to the present invention is shown as applied to an electric branch clock, the strike work being adapted to strike full and half hours.

Fig. 1 is a rear elevation of the strike work 35 as a whole.

Fig. 2 is another rear elevation showing the parts of the work which are hidden behind other parts in Fig. 1.

Figure 2^a is another rear elevation showing 40 the coaction of parts illustrated in Figures 1 and 2.

Figure 2^b is a side elevation of the clock mechanism.

Fig. 3 is a vertical cross-section of the 45 right hand part of Fig. 1.

Figs. 4 and 5 are details.

Referring to Figs. 1 and 2, 1 is the magnet coil of the branch clock adapted to receive 50 through the main line 2 a short current impulse serving for moving the hands 7, 8 arranged at the front of the base plate 0. To this end the magnet coil is disposed on the permanent magnet 3. The detail mechanism

by which this is accomplished is immaterial for the purpose of the present application. 55 It is sufficient to assume that the coils of the electromagnet are fixed with their cores to the permanent magnet 3 by means of bracket 3^a (Figures 2^a, 2^b). In the magnet circuit of the pole pieces 3' of this magnet, 60 an S-shaped armature 4 is rotatably located, said armature being caused by each current impulse transmitted through the line wire, to move on in the same direction (clockwise in Figure 2^b) and causing in turn, by means 65 of a worm 5 and gear wheel 6, the hands 7 and 8 to travel around. Near the end of each hour a longer current impulse is transmitted to the work, said impulse not only causing the hands to move, but also supplying 70 the current required for the operation of the strike work. The strike work itself is actuated by means of a series of excitations, corresponding to the number of strokes, of a strike work magnet 20 connected 75 in parallel to the clock magnet 1, the current supply of magnet 20 being started by the clock work and controlled by the strike work itself. The current impulse transmitted at the end of each hour should last long enough 80 to allow the strike work to strike full twelve hours. For the half hours the usual impulse transmitted every minute and serving to keep the clock going will suffice. A current impulse of greater duration may be transmitted to the clock also every half hour. 85

The arbor of the minute hand 7 carries a disk 9 provided with two diametrically opposite pins 10 (Fig. 2), these pins being adapted to cooperate with an angular lever 90 12 (the releasing lever) fixed on an axle 11 in such a manner that the said lever is lifted before the end of each half and full hour and will slip off exactly at the end of the half or full hours. On the lever axle 11 there is further fastened a pawl 13 engaging with the teeth 14 of a segment rack 15 adapted to rock on an axle 16. Upon lever 12 being lifted pawl 13 withdraws from between the teeth of the rack, thus allowing the latter to 100 rock on its pivot 16 in a downward direction until a pin 17 fastened to it meets the periphery of a step disk 18 fastened to the wheel coupled with the hour hand 8 (see Figure 2^b).

As soon as lever 12 has slipped off a pin

10, which will be the case at the end of each full and each half hour, the strike work is set going. The pawl 13 now meshes again with one of the teeth 14 whose distance from 5 the first tooth, according to the position of the step disk 18, corresponds to the length of the row of teeth which equals the number of strokes required to indicate the respective hour. Therefore, if the rack is 10 moved upwards during the act of striking and if an individual stroke corresponds to each tooth of the rack, then the number of strokes is dependent upon the step disk and upon the position of the hands.

15 The rack is caused to move upwards by the strike work magnet 20 attracting its armature 21 pivoted at 19 and being influenced by a spring 45', thus causing a bell crank 25 pivoted at 23 and carrying a 20 toothed segment 24 to rock (Figs. 2, 2^a). The strike work magnet 20 is connected in parallel with the clock magnet 1 over a contact device which will be described in detail below. The toothed segment is in gear with 25 a pinion 26 retarded in both directions by means of a fly 28 geared to it by gear wheels 27, 27', gear 27 carrying a feeding pawl 29 (Fig. 4) which feeds a notched disk 30 along, when the gear wheel 27 is rotating 30 (clockwise as seen in Fig. 2). Coupled with disk 30, is a disk 30' (Figs. 3 and 4) which carries two pins 31 arranged diametrically opposite each other and engaging alternately the teeth 14 of the rack 15 so as to 35 cause the rack to move upwards by one tooth whenever the armature 21 is being attracted. Upon the armature falling off, disk 30 remains stationary, while feeding pawl 29 thereby disengaging from disk 30 40 retaining pawl 33, suitably attached to the housing, engages notches provided in disk 30' and prevents this disk from turning backward. The rack is held in its position by the pawl 13 until it is lifted another tooth 45 by a pin 31 when the armature is attracted once more. The contact device controlling the circuit of magnet 20 is actuated by the upward movement of rack 14 which, on reaching its uppermost position, causes a 50 pin 34 arranged on the rack to cut off the supply of current to magnet 20 by means of a lever 35, as will be described more fully hereinafter.

55 While the rack is moving upwards, the strike work is actuated. The striker 37 influencing the gong spring 36 is fixed on a rotatable axle 38 carrying a block 39 (Fig. 2) controlled by a spring 40 so as to have a tendency to remain in its position of rest 60 and prevent the striker from coming in contact with the gong spring or bell after having once struck it. Block 39 is provided with an indenture 41; a pawl 42 pivotally attached to the toothed segment lever 25 65 and yieldingly held against a stop 43' by a spring 43 catches in said indenture 41 as soon as the armature 21 is attracted, thus causing striker 37 to be lifted each time the armature is being attracted. In order to allow striker 37 to slip off suddenly the 70 ratio of moving of pawl 42 and block 39 is chosen in such a manner that after the striker has been lifted through the necessary distance, the pawl will slip off the lower edge of indenture 41, thus allowing the 75 striker to descend freely. At the same time pawl 42 comes to rest on the projecting surface 42'. As soon as magnet 20 is de-energized, the armature is released and under the action of spring 45' pawl 42 returns 80 into its normal position as shown in Figs. 2 and 2^a.

85 The current supply to magnet 20 is controlled by a number of contact springs 45, 46, 47 (Fig. 1). Spring 45 is connected to one pole of the line 2, while springs 46, 47 are connected to the other pole over the magnet winding. Spring 46 is influenced by the releasing lever 12, pawl 42 and rack 15; 90 spring 47 by the striker 37.

95 The connections for actuating the strike work are as follows: So long as the strike work is at rest, contact spring 47 rests on a flattened portion provided on the insulating block 48 fixed to the striker axle 38, contacts 47, 45 being then open. Spring 46 is removable from spring 45 by an insulating finger 49 arranged on a bell crank lever 50 provided at its other end with a fork 51 embracing a pin 52, said pin being arranged 100 on a disk 54 fixed on an axle 53. Lever 50 is spring controlled as shown at 50' in Figure 1, so that it tends to stand in the position shown in that figure, permitting springs 45, 46 to contact with each other. Axle 53 105 is coupled by means of toothed gear 55 with another axle 53', carrying the lever 35 which in turn, under the influence of spring 50', tends to stand in the position shown in Figures 2 and 2^a. Lever 35 is swung to the 110 right (Figure 2) by pin 34 arranged on rack 15, whenever the latter has reached its uppermost position (in Figures 2 and 2^a the pin has just left the lever 35). In accordance with this arrangement whenever the 115 strike work is at rest, the contact 45, 46 is open also, and the strike magnet 20 receives no current.

120 Towards the end of each half and full hour, one of the pins 10 meets the releasing lever 12 which is lifted more or less according to the radial position of the pin in engagement with it. The half hour strike will be referred to in detail later on. By the 125 rocking of the releasing lever, pawl 13 is removed from the rack which falls down by gravity onto the stepwheel at the end of each full hour, while for the half hours it only drops part way as will be explained later on. When the rack drops, pin 34 re- 130

leases lever 35 permitting it to swing to the left, so that by means of gear 55, pin 52 and lever 50, insulating finger 49 (Figures 1, 2^a) is removed from spring 46. The normal 5 tension of spring 46 would now close contact 45, 46 were it not prevented at that moment by an insulating cam 56, fixed on axle 11 of lever 12. When releasing lever 12 is lifted by one of pins 10, this cam rocks to the 10 right (Figures 1 and 2^a) and engages spring 46, thereby holding it away from spring 45. Exactly at the end of a half or a full hour, releasing lever 12 slips off the pin 10 with which it is then in engagement. Insulating 15 cam 56 rocks back to the left, which releases spring 46, so that springs 45 and 46 come into contact. The magnet 20 is now supplied with current so as to attract its armature 21. The attraction of this armature is 20 retarded by fly 28, described before. The striker 37 is now raised by this armature movement to the point where pawl 42 slips off block 39 as has also been described before, permitting the striker to then freely 25 descend onto gong 36.

In order to bring the release of the strike magnet armature under the control of the striker, the following arrangement is provided:

30 While the striker is raised, the flattened insulated block 48 fixed to its axle 38 and against which contact spring 47 rests, causes that spring to come in contact with spring 45, thus forming a shunt around contacts 45, 46 35 in circuit with magnet 20. Now pawl 42, gliding on projection 42', immediately before the striker reaches its uppermost positions, depresses by aid of a pin 60, a lever 57 fixed to axle 53, thus turning finger 49 to 40 the right (Figures 1 and 2^a) and opening thereby contacts 45, 46. The opening of these contacts and closing of contacts 45, 47 brings the opening of the magnet circuit under the control of the striker 37, because now 45 that circuit is opened at contacts 45, 47 as soon as the striker descends and releases spring 47.

When the armature 21 has been returned slowly to its position of rest by spring 45' 50 under the retarding action of fly 28, the toothed segment 24 is ready to lift the rack further, and pawl 42, having then slipped off the projection 42' of block 39 back into alinement with notch 41, permits its pin 60 55 also to release lever 57 and bell crank 50 with its finger 49, thus allowing contacts 46, 45 to close and magnet 20 to be again supplied with current. In this way, the cycle of op-

eration will be started anew until the rack has ascended to its uppermost position, 60 where pin 34 causes contacts 46, 45 to be opened by aid of lever 35, axles 53 and 53', bell crank 50 and finger 49. This restores the strike work to its position of rest.

Since the armature has a retarded motion 65 the striker has reached its position of rest before the armature has reached its rest position. The striker descending unencumbered by its lifting mechanism, performs its stroke with full strength, while the retardation of 70 the armature movement to its position of rest secures noislessness, so that the sound of the gong is not disturbed by extraneous noises.

In order to be able to indicate the half 75 hours by aid of a single stroke, the following arrangement is provided: As shown in Fig. 5 the first tooth 58 of the rack is somewhat lower than the rest and the releasing pin 10 for the half hours is arranged at a smaller 80 distance from the center of the releasing disk 9, so as to cause the pawl 13 of releasing lever 12 to release only tooth 58, but to be caught again by the normal size tooth 59 next following. In this manner only a single 85 stroke is produced.

The strike work of the clock instead of being fed from the clock supply line, may as well be fed from a battery or from a light or power current supply.

90

I claim:—

1. In an electrically actuated clock in combination a rack strike work, an electromagnet adapted to only drive said strike work, an armature actuated by said magnet, means 95 permanently connected to said armature and operated by the same for lifting the striker, retarding means permanently connected to said lifting means, and means for releasing the striker from all its operating elements 100 when it has reached its uppermost position.

2. In an electrically actuated clock in combination a rack pivotally disposed, an electromagnet adapted to only drive said striker, an armature actuated by said magnet, a lever 105 permanently connected to said armature for lifting the striker, retarding means permanently connected to said lever, a block fixed on the pivot of said striker, said block having an indenture, a pawl journaled on said 110 lever and adapted to engage said indenture when the armature is attracted and to slip off when the striker has reached its uppermost position.

PAUL MANSEL.
